UNITED STATES PATENT OFFICE.

JAMES H. THOMPSON, OF TRENTON, NEW JERSEY, ASSIGNEE TO HUSSONG DYEING MACHINE COMPANY, OF GROVEVILLE, NEW JERSEY, A CORPORATION OF NEW JERSEY.

APPARATUS FOR DYEING RAW STOCK.

Application filed July 9, 1925. Serial No. 42,484.

To all whom it may concern:

Be it known that I, JAMES H. THOMPSON, a citizen of the United States, residing in Trenton, Mercer County, New Jersey, have 5 invented certain Improvements in Apparatus for Dyeing Raw Stock, of which the following is a specification.

My invention relates to certain improvements in dyeing machines, in which the 10 stock to be dyed is placed in a cage in a loose condition, and the dye liquor is circulated through the cage—first in one direction and then in a reverse direction.

The object of the invention is to construct 15 a cage, including a top therefor, all of which is removable with the cover of the dye vat, and to provide the cage with hinged bottom sections that can be opened to allow the material to be discharged from the cage.

20 In the accompanying drawings:

Fig. 1 is a plan view of a dye vat illustrating my invention, the cover of the vat being broken away to show the top of the cage;

25 Fig. 2 is a side view of the cage;

Fig. 3 is a transverse sectional view of a dye vat, showing the cage in position therein;

30 Fig. 4 is an end view of the cage, elevated clear of the vat after the material has been dyed;

Fig. 5 is a view showing the bottom sections of the cage open to allow the material to be discharged from the cage; and

35 Fig. 6 is a view of the cage, showing the bottom closed and the top detached from the cage to allow the cage to be loaded.

The vat 1 can be of any suitable construction, and is preferably provided with means 40 for circulating the dye liquor—first in one direction and then in the opposite direction. Such a vat is shown in the patent granted to Joseph Hussong on June 5, 1906, No. 822,844.

45 The cage 2 fits the dyeing section of the vat 1 and has metallic straps 3, which extend through slots in the beams 4 of a beam structure 5, which rests on the upper edge of the vat. Wedges 6 are driven through 50 slots in the straps. These wedges can be removed when it is desired to detach the cage from the beams.

The bottom 7 of the cage is made of hinged sections 8, which are suitably braced

to support the load. Each section is perforated for the passage of the dye liquor. The sides of the cage are connected by transverse bolts 9, which extend through tubes 10. The tubes and bolts act to brace the sides of the cage.

The top section 11 of the cage is suspended from the longitudinal beams 12 of the beam structure 5 and are bolted to the transverse beams 4. Bolts 13 extend through tubes 14 and rigidly secure the top section of the 65 cage to the beams. This top section is shown as made in two parts. Each part is flanged, as at 15. Longitudinal bars 16 extend the full length of the top section and are firmly secured to the sections of the top. 70 The sections are perforated to allow the dye liquor to circulate freely. At one end of one of the top sections is a hinged sample door 17, which is held in the closed position by a catch. On opening this door, a sample of 75 the stock being dyed can be removed for inspection.

The cover 18 of the vat is secured to the upper surface of the beams 12 and extends over the edge of the vat when the cage is 80 in the vat, as in Fig. 3.

The cover has a door 19, which is directly above the sample door 17. The cage is loaded with material outside of the vat. The bottom of the cage is closed, as in Fig. 85 6, and the top is raised by any suitable hoist. After the cage is filled with material, the cover is lowered into position and the wedges are driven to secure the cage to the cover, as in Fig. 4. Then the cage is lowered into the vat, as in Fig. 3. The cover 18 of the vat rests on the top thereof and the top 11 of the cage is suspended within the cage.

After the material in the cage has been 95 dyed, the cage is lifted out of the vat with the cover, as illustrated in Fig. 4, and is removed to the place where it is desired to discharge the dyed material. While the cage is suspended, the material is discharged. 100 The doors are then closed and the cage is lowered onto a truck, or other suitable support, as shown in Fig. 6. The top and cover are disconnected from the cage and are raised clear thereof to allow the cage to be 105 reloaded with material to be dyed.

By making the top of the cage detachable and removable with the cover of the vat, free

access to the cage is assured, as is the proper loading of the material to be dyed.

I claim:

1. The combination in a dyeing machine for raw stock, of a vat; a cage arranged to be located therein and having a perforated bottom arranged to be opened; a beam structure resting on the vat; means for detachably securing the cage to the beam structure; and a top for the cage, which is suspended from the beam structure.

2. The combination in a dyeing machine for raw stock, of a vat; a beam structure arranged to rest on the vat; a cage located within the vat and detachably suspended from the beam structure; a perforated, movable bottom for the cage; a perforated top for the cage, which is suspended from the beam structure independently of the cage;

and a cover for the vat carried by the beam structure.

3. The combination in a dyeing machine for raw stock, of a vat; a cage; a beam structure for suspending the cage within the vat; and a perforated cover for the cage secured to said beam structure, the cover being flanged and having longitudinal strengthening bars.

4. The combination in a dyeing machine for raw stock, of a vat; a cage; beams from which the cage is suspended; and a cover for the vat secured to the beams independently of the cage, said cover being made in sections and having angle bars connecting the sections together and strengthening the cover, each section of the cover being perforated and flanged.

JAMES H. THOMPSON.
